UNITED STATES PATENT OFFICE

PETER GRAHAM MACGREGOR, OF PEQUANNOCK, NEW JERSEY, ASSIGNOR TO PYRENE MANUFACTURING COMPANY, OF NEWARK, NEW JERSEY, A CORPORATION OF DELAWARE

FIRE EXTINGUISHING APPARATUS

Application filed November 1, 1927. Serial No. 230,239.

This invention relates to fire extinguishing apparatus particularly adapted to be installed upon and used in connection with motion picture projectors, although it is capable of other use.

When a motion picture film of the inflammable type takes fire, it is of vital importance that the fire be extinguished at the earliest possible moment, because the process of combustion liberates oxygen at a rate sufficient to support combustion if the fire continues for any appreciable length of time, thereby making it practically impossible to extinguish it until the film has been destroyed. The general object of the present invention, therefore, may be said to be the providing of a new and improved fire extinguishing apparatus which will automatically function when a film is ignited to extinguish the fire in the shortest possible period of time after it commences.

Other objects and advantages of the invention will become apparent from the following description, taken in connection with the accompanying drawings, in which:

Figure 1 is a fragmental side elevation of a motion picture projection apparatus, having the apparatus embodying the invention applied thereto; Figure 2 is a fragmental side elevation of the upper part of the machine, as viewed from the rear in Figure 1; Figure 3 is a fragmental view, partly in section and partly in elevation, of the reservoir for the fire extinguishing liquid, as viewed from the left in Figure 1; Figure 4 is a detailed vertical sectional view of a releasable flash-pan or cage and valve mechanism; Figure 5 is a plan view of the flash-pan, as viewed from above in Figure 4; Figure 6 is a detailed view showing in section and in elevation a pressure actuated switch operating mechanism; Figure 7 is a vertical sectional view of the cartridge holder and cartridge puncturing mechanism; Figure 8 is a view in elevation of the holder and puncturing mechanism, as viewed from the right in Figure 7; Figure 9 is a horizontal

sectional view, taken on line 9—9 of Figure 7; and Figure 10 is a horizontal, sectional view, taken on the line 10—10 of Figure 7.

The apparatus embodying this invention is adapted to be installed upon a motion picture apparatus having upper and lower reel compartments 10 and 11, and an intermediate compartment 12, adapted for the reception of the usual film operating mechanism. The apparatus includes a reservoir 13, adapted for the reception of a fire extinguishing liquid; and also includes a cartridge holder and cartridge puncturing mechanism 14, which puncturing mechanism is adapted to be automatically actuated, when a fire occurs, to puncture the cartridge and release its contents into the receptacle 13, whereby the liquid contents of the receptacle is forced out through a suitable pipe line 15 to various parts of the motion picture apparatus.

The receptacle 13, which is adapted for the reception of the fire extinguishing liquid, is mounted upon the film compartment 10 by a suitable bracket 17 and is provided at its upper end with a neck 18, having a filling passage 19 and a valve seat 20, which is adapted for the reception of a valve 21, the stem of which is provided with a hand wheel 22, and is mounted for screw-threaded adjustment in a yoke 23 pivotally connected to the neck 18 by screws 24. By this valve arrangement, the receptacle 13 may be readily opened to permit filling by so rotating the hand wheel 22 as to lift the valve 21 clear of the neck 18, thus permitting the yoke 23 with the valve 21 to be swung outwardly and downwardly to its dotted line position shown in Figure 3. Likewise, the receptacle 13 may be readily closed after filling, by moving the yoke 23 to its full line position shown in Figures 1 and 2, and then screwing the valve 21 down into engagement with its seat 20.

Within the receptacle 13, is arranged a discharge tube 25, which terminates near the bottom of the receptacle and projects from

the top thereof where it is connected to the pipe line 15, which includes a plurality pipe line sections 26 from certain of which spray nozzles 27, 28 and 29 lead to the upper and 5 lower reel compartments 10 and 11 and the intermediate compartment 12, the spray nozzles being adapted to direct the fire extinguishing liquid into the respective compartments where a film conflagration is most 10 likely to occur or to where such conflagration is likely to spread.

The cartridge holder and cartridge puncturing mechanism, shown in detail in Figures 7 to 10, 14 is suitably supported adjacent the upper reel compartment 10, and includes a barrel 31 within which is confined a compression spring 32, the lower end of which engages the bottom of a removable screw-threaded cap 33 carried by the barrel 31, and the upper end of which engages an impact hammer 34, slidably mounted within the barrel 31. Within this impact hammer 34 is slidably mounted a rod 35, the upper end of which is provided with a flange 36 25 and a piercing punch 37, which projects through a stuffing box 38, mounted in the lower end of a housing 39. The impact hammer 34 is provided at its lower end with an annular groove, which forms a shoulder 40 30 adapted to cooperate with a trigger latch 41, mounted in one of a pair of diametrically opposed slots 43 formed in the barrel 31, the trigger 41 being normally urged inwardly by a flat spring 44, secured to the barrel 31 35 and maintained in engagement with the trigger 41 at a point adjacent the outwardly projecting notched arm 45 thereof. The trigger 41, when positioned as shown in Figure 7, is adapted to hold the impact hammer 34 in its 40 retracted position against the pressure of the spring 32, and is adapted to release such hammer when a fire occurs, as will hereinafter be explained, so as to allow the hammer 34 to move into engagement with the 45 flange 36, thus forcing the punch 37 upwardly and through one end of a cartridge 47 which is removably seated in a cartridge cup 48 and carries a quantity of liquefied gas, such as carbon dioxide. The cartridge cup 50 48 is provided with a reduced screw-threaded end which is threaded into the upper end of the housing 39, and is maintained in engagement with a packing ring 49 seated upon the upper or flanged end of the stuffing box 38. 55 The stuffing box 38 is counter-bored to provide a pressure chamber 51, into which projects the neck of the cartridge 47, which is surrounded and gripped by the packing ring 49, the pressure chamber 51 being connected with the upper end of the receptacle 13 by a pipe 52.

The cartridge 47 is held in its seated position by a pressure screw 53 having screw-threaded engagement with the cross member 5 of a yoke 54, the arms of which are pivotally

connected at their lower end to the housing 39 by a pair of pins 55. When it is desired to remove the cartridge 47 to permit replacement thereof, the pressure screw 53 is unscrewed until it is free from the cartridge 47, 70 whereupon the yoke 54 may be swung about its pivotal connection with the housing 39 to its dotted line position shown in Figure 8. As the yoke is thus swung about its pivotal connection, a pair of guides 56, which are 75 slidably mounted in the slots 43 and are connected to the yoke 54 by a pair of links 57, are moved downwardly. These guides 56 are provided with inwardly projecting lugs 58 which are adapted to engage the upper end 80 of the impact hammer 34, after such hammer has been released from its retracted position, shown in Figure 7. It will thus be appreciated that the movement of the yoke 54 which permits the removal of a discharged 85 cartridge, may be utilized to reset the impact hammer 34 preparatory to substituting a new cartridge for the one previously discharged.

In the pipe line 15 is arranged a normally closed valve 59 which includes a housing 64, 90 having a chamber 50 therein, within which is carried a longitudinally movable valve plunger 42. This valve plunger 42 is formed at one end with a valve tip 42' adapted to engage a valve seat formed in the wall of the 95 valve housing 64 at the outlet end of the pipe line section 26 leading into the chamber 50 from the reservoir 13. The other end of the valve plunger 42 projects through the bottom of the housing 64 and is formed with an annular flange 42'' adapted to engage the bottom of the housing 64 and thereby limit the longitudinal movement of the valve plunger 42 as such valve plunger moves by gravity 100 and under the influence of the fire extinguishing liquid coming through the pipe section 26 when a fire occurs, to open the outlet end of the pipe line section 26 leading into the chamber 50 from the reservoir 13. The valve plunger 42 is normally held closed by a V-shaped valve retaining spring 65, one arm of 110 which engages the lower end of the valve plunger and the other arm of which is secured to the bottom of a flash-pan or cage 60. This flash-pan 60 is preferably perforated 115 and is pivotally connected to a suitable support, such as the housing 64 of valve 59, and is adapted for the reception of a quantity of gun cotton, not shown, or other highly inflammable material, which is ignited by the 120 passage of a flame from the compartment 12 through an opening 62 formed therein, it being in this compartment that the film ignites from the heat of the light rays issuing from the light projector 63 of the motion picture apparatus.

For locking the pan 60 in its normal position, a fusible link 66 is employed, the link being supported at one end by a pin 67, carried by a suitable fixed part of the apparatus, 13

and supported at its other end upon one end of a horizontally disposed arm 68, which is pivotally connected intermediate its ends to a suitable stationary support. The arm 68 is pivotally connected at its outer end to a connecting link 69, which in turn is pivotally connected to a trigger releasing lever 70, pivotally connected near its upper end to the barrel 31 and having its upper end projecting into the notched arm 45 of the trigger 41. Cooperating with the fusible link 66 is a removable pin 72 carried by one side of the flash-pan 60 and adapted to be projected into the space afforded intermediate the upper and lower reaches of the fusible link. Due to the position of the pin 72 with reference to the fusible link 66, such link serves to retain the flash-pan 60 normally in its position shown in Figure 4. However, when the link 66 is fused, the supporting relation of such link with respect to the pin 72 is destroyed, and the flash-pan 60 is allowed to drop, thus permitting the valve 59 to open by gravity and allowing the horizontally disposed link 69 to move to the left, as viewed in Figures 1 and 5, under the influence of a tension spring 74 (Figure 1), having one end connected to such link and its other end anchored to a stationary part of the apparatus. As the link 69 is thus moved, the lever 70 is so actuated as to move the trigger 41 outwardly, thereby releasing the impact hammer 34, whereupon the spring 32 forces it against the flange 36 on the rod 35, with sufficient impact to force the pointed end of the piercing punch 37 through the bottom of the cartridge 47. As the cartridge is pierced, its contents escapes into the chamber 51 as a gas under pressure which is directed into the reservoir 13 through the pipe 52, with the result that the fire extinguishing liquid in the reservoir is forced through the pipe line sections 26 and distributed through the several nozzles 27, 28 and 29 thereof to the upper and lower reel compartments 10 and 11 and the intermediate compartment 12.

The neck 18 of the receptacle 13 is formed with a vent passage 77 which terminates at the valve seat 20. This vent passage 77 is maintained in communication with the pipe line 15 by an anti-siphon tube 76. Inasmuch as the vent passage 77 terminates at the valve seat 20, the pipe line 15 is opened to the atmosphere by opening the valve 21. Therefore, when the valve 21 is opened to free the receptacle 13 of pressure when the apparatus has been accidentally operated, for example, by the breaking of the fuse link 66 in the absence of a fire, opening of the pipe line 15 to the atmosphere is insured. By thus opening the pipe line 15 to the atmosphere, any liquid remaining in the receptacle 13, after the pressure has been released therefrom by opening the valve 21 to prevent forced operation of the apparatus, cannot be siphoned

out through the pipe line 15, inasmuch as such liquid as remains therein intermediate the highest point in such line and the lowermost thereof, is permitted to drain, without disturbing the remaining contents of the receptacle.

In case of a fire, the motor 78, employed for operating the film moving mechanism of the picture projecting apparatus should be instantly stopped. To accomplish this, an auxiliary switch 80 (Figure 6) is disposed in the motor circuit, in addition to a main switch, not shown. This auxiliary switch 80 may be of the usual double-push-button type, with the circuit-opening button 81 of which is associated a cylinder 82, containing a slidably mounted piston 83. The piston 83 is adapted to engage the push button 81 and move it inwardly when gas pressure from the cartridge is delivered to the outer end of the pressure chamber 82, through a pipe 84 which is suitably connected to the pipe 52 and is thus in communication with the pressure chamber 51. From this arrangement, it will be appreciated that when the cartridge 47 is punctured, pressure will be supplied to the pressure chamber 82, with the result that the piston 83 carried therein is so moved as to force the push button 81 inwardly, thereby opening the motor circuit through the auxiliary switch 80.

In operation, should a fire occur in the compartment 12, the flame will pass through the opening 62 adjacent the flash-pan 60, with the result that the gun cotton or other highly inflammable material carried by such pan will become ignited, and the link 66 will be fused. When the link 66 fuses, the flash-pan 60 will drop by gravity, thus allowing the valve 59 in the pipe line 26 to open. The instant the fuse link 66 separates, the connecting link 69 is moved by the action of the spring 74 towards the left, as viewed in Figures 1, 5 and 7, with the result that the trigger 41 is disengaged from the impact hammer 34, whereupon such hammer, acting under the influence of the compression spring 32, delivers a blow to the guide rod 35 and thereby forces the piercing punch 37 through the wall of the cartridge 47. As the cartridge 47 is punctured, its contents is delivered to the pressure chamber 51 as a gas under pressure, and thence into the receptacle 13 through the pipe 52. The pressure so delivered to the receptacle 13, forces the contents of such receptacle up through the discharge tube 25 and into the pipe line 15, from which it is injected into the compartments 10, 11 and 12 to extinguish the fire. Of course it is obvious that the carbon dioxide contents of the cartridge, when released, first expels the fire extinguishing liquid from the receptacle 13, and then passes through the pipe line 15 into the compartments 10, 11 and 12 where it serves as a fire

extinguishing gas augmenting the action of the previously delivered fire extinguishing liquid. In the meantime, gas under pressure delivered to the cylinder 82 serves to move 5 the piston 83 towards the left, as viewed in Figure 6, and thereby open the motor circuit through the auxiliary switch 80 at substantially the instant the fire occurs.

After the fire has been extinguished, the 10 receptacle 13 may be re-filled by removing the valve 21 from its valve seat 20 and swinging the same to its dotted line position in Figure 3. The receptacle 13 is then closed by swinging the valve to its vertical position 15 and screwing the same down into sealing engagement with its seat 20. The discharged cartridge 47 may be readily removed by releasing the pressure screw 53 and swinging the yoke 54 to its dotted line position, shown 20 in Figure 8. In swinging the yoke 54 to its dotted line position shown in Figure 8, the guides 56 are moved downwardly within their respective slots 43 and serve to reset the impact hammer 34, as shown in Figure 25 7. After replacing the cartridge 47, the yoke 54 is moved to its vertical position, and the pressure screw 53 is then run down into engagement with such cartridge, thereby locking the same in position for use.

30 Of course, before inserting the new cartridge and setting the puncturing device, the link 69 is locked in its retracted position by placing a new fuse link 66 on the end of the pin 67 and the end of the lever 68, as shown 35 in Figures 4 and 5. With the link 66 so positioned, the flash-pan 60 may be locked in its normal position, shown in Figures 1 and 4, by passing the pin 72 through one of the side walls of such pan and into the space afforded 40 between the upper and lower reaches of the fuse link. The flash-pan in its locked position cooperates with the valve retaining spring 65 and thereby serves to hold the valve 59 closed.

45 While only one form of the invention has been herein shown and described, it will be understood that various modifications and changes may be resorted to without departing from the spirit of the invention or the 50 scope of the following claim.

What is claimed is:

In combination with a motion picture projector having a film housing provided with 55 an opening, a cage movably mounted adjacent said opening and adapted to contain a highly inflammable material, fusible thermal release means for holding said cage in a suspended position and adapted when fused to release said cage, a liquid receptacle adapted to contain a fire extinguishing liquid, a conduit leading from said receptacle into said housing, a valve in said conduit cooperating with said cage and retained closed by the latter when said cage is in its suspended position 60 and permitted to open when said cage is re-

leased, a source of fluid pressure, means for releasing said fluid pressure and directing it into said receptacle for expelling the contents of the latter through said conduit, and means cooperating with said thermal release means for rendering said fluid releasing means inoperative until said thermal release means is fused. 70

In testimony whereof, I have affixed my 75 signature to this specification.

PETER GRAHAM MACGREGOR.
